UNITED STATES PATENT OFFICE

NORMAN L. SNOW, OF NEW CANAAN, CONNECTICUT, ASSIGNOR TO DIAMOND POWER SPECIALTY CORPORATION, OF DETROIT, MICHIGAN, A CORPORATION OF MICHIGAN

BOILER CLEANER

Application filed November 12, 1923, Serial No. 674,344. Renewed October 10, 1930.

The invention relates to boiler cleaners and is designed particularly for use in boiler cleaners of that type having an intermeshing worm and worm wheel for respectively opening and closing the valve and rotating the blower element.

Heretofore, in boiler cleaners of this type, it has been found that the valve controlling the admission of steam to the blower element has partially closed before rotation of the blower element has been completed so that the full effect of the steam jets upon the boiler tubes has not been secured, and as a consequence, the boiler cleaner has functioned inefficiently. The most common cause for this faulty operation is the excessive friction offered to the rotation of the blower element such as by reason of its warping and consequent binding in the bearings.

With my invention, an unbalanced force is applied to the valve when in open position and acting in a direction opposite to that taken by the valve in moving to closed position whereby rotation of the blower element is necessarily completed before the valve is moved from its open position toward its closed position. With this as well as other objects in view, the invention resides in the novel features of construction and combinations and arrangements of parts as more fully hereinafter set forth.

In the drawings:

Figure 1 is a plan view of a blower unit embodying my invention;

Figure 2 is a cross section on the line 2—2 of Figure 1;

Figure 3 is a cross section on the line 3—3 of Figure 2;

Figures 4, 5 and 6 are views similar to Figure 2, but showing modified constructions.

As shown in Figures 1, 2 and 3, 1 is the blower unit and 2 the boiler wall through which extends the blower element 3 having nozzles through which the cleaning fluid such as steam or the like is discharged upon the boiler tubes. 4 is the worm wheel secured to the outer end of the blower element, and 5 is the worm meshing with the worm wheel 4. The shaft 6 of this worm is journalled in the

50 casing 7 for the worm and worm wheel and

extends outwardly therethrough, one end of the shaft being coupled to suitable driving means and the other end of the shaft being connected to the valve 8 which controls the admission of the steam or the like to the 55 blower element 3.

The valve 8 is located within the casing 9 having the partition 10 provided with the port 11 which is adapted to be closed by the valve. The steam or the like enters the casing through the inlet passageway 12, passes through the port 11 when the valve is in open position and then passes through the conduit 13 to the casing 14, which latter is located between the gear casing 7 and the 60 boiler wall 2. The casing 14 surrounds the portion of the blower element between the gear casing and boiler wall and communicates with the interior of this blower element through the ports 15 in the blower element. The worm shaft 6 is longitudinally 65 slideable in the casing 7 for the purpose of correspondingly moving the valve 8 to open and closed positions. The rotation of the worm wheel 4 in opposite directions is suitably limited as by means of the lug 16 upon the gear casing 7 and the transverse pin 17 upon the worm wheel engageable with opposite sides of the lug. Under actual operating conditions, the blower element is liable 70 to stick thereby requiring considerable force to rotate the same. With the valve in open position and the blower element in its adjusted position of rotative adjustment, it has been found that upon reversing the rotation 75 of the worm shaft, the valve has partially closed prior to the rotation of the blower element and remained in this condition until the rotation of the blower element has been completed. This is very inefficient and 80 therefore objectionable, and to overcome this faulty operation, I have provided an unbalanced force acting upon the valve in a direction opposite to that taken in moving the valve to closed position, this unbalanced force being sufficient to retain the valve in open position until the blower element has been completely rotated to its original position.

As shown particularly in Figure 2, 18 is 100

a piston between the valve 8 and worm 5 and slideable in the valve casing 9. This piston connects the worm shaft to the valve and has an end area such that when the valve is in open position and steam or the like is being admitted through the port 11 and is exerting its pressure upon the end of the piston, a sufficient force is created to retain the valve in open position and compel the rotation of the blower element to its original position upon rotation of the worm shaft. As soon as the blower element has been returned to its original position and the rotation of the worm wheel is limited by its transverse pin 17 coming into contact with the stop lug 16, the valve will then be returned to closed position by the re-action of the teeth of the worm upon the teeth of the worm wheel. Since the valve moves to open position in the direction taken by the steam or the like in entering the valve casing, the moving of the valve to open position before the rotation of the blower element is assured. With the valve in closed position and the blower element in its normal position, rotation of the worm shaft first causes a longitudinal movement of the worm by the re-action of its teeth and the teeth of the worm wheel. When the worm comes into contact with the bushing 7' surrounding the worm shaft and located within the gear housing, its longitudinal movement is stopped and continued rotation of the worm shaft then causes the blower element to rotate until limited by the cooperating stops upon the worm and gear housing.

In the modified construction shown in Figure 4, the valve 19 for controlling the admission of steam or the like to the blower element is moved in the direction opposite to that taken by the valve 8 of the above construction. That is, the valve 19 is moved away from its seat and to open position against the force created by the steam which enters through the inlet passageway 20 of the valve casing 21. The piston 22 is connected to the valve 19 at its outer end, and is slideable in the cylindrical flange 23 of the casing. With this arrangement, the steam or the like is at all times creating an unbalanced force upon the valve to hold the same in open position. As a consequence, when the valve is in closed position and the blower element is in its initial position, movement of the valve to its open position is assured upon rotation of the worm shaft and longitudinal movement of the worm effected through the reaction between its teeth and the teeth of the worm wheel. After the valve has opened and the end of the worm has come into contact with the stop 24 within the gear housing and surrounding the worm shaft, further rotation of the worm shaft causes rotation of the worm wheel and blower element until the cooperating stops

come into contact. Upon reverse rotation of the worm shaft, longitudinal movement of the worm and consequent movement of the valve is prevented by the pressure of the steam or the like exerted upon the piston until rotation of the blower element has been completed, after which the valve is closed by the reaction between the teeth of the worm and worm wheel. 70

In the modification shown in Figure 5, the same general arrangement of parts is present with the exception that the unbalanced force is created by a spring instead of by the steam or the like acting upon the piston. As shown, 36 is a coil spring within the gear housing 37 and surrounding the worm shaft 38. This coil spring abuts the washer 39 at the end of the worm 40 and also the end of the gear housing, the arrangement being such that the coil spring creates an unbalanced force tending at all times to move the valve 41 secured to the worm shaft toward its open position. 75

In the modified construction shown in Figure 6, the unbalanced force is created by means of gravity. In detail, 42 is a lever pivoted intermediate its ends upon the gear housing 43. The upper end of this lever embraces the worm shaft 44 and has an edge engaging the transverse pin 45 upon the worm shaft. The lower end of the lever is secured to the cable 46 which runs over the pulley 47 journaled upon the arm 48 extending laterally from the gear housing. 49 is a weight connected to the cable and of sufficient size to exert an unbalanced force upon the worm shaft, and consequently the valve, to tend to move the same to open position and to retain the same in open position until the blower element has been returned to its original position. 80

What I claim as my invention is:

1. In a boiler cleaner, the combination with a blower element adapted to discharge steam or the like, of a valve for admitting steam or the like to said blower element, common means for actuating said blower element and opening and closing said valve, means distinct from said valve and in addition to said valve actuating means for effecting an unbalanced force upon said valve when in open position acting in a direction opposite to that taken by the valve in moving to closed position, whereby the actuation of said blower element is completed before the valve is moved from open position, and means limiting the travel of the blower element. 105

2. In a boiler cleaner, the combination with a rotatable blower element adapted to discharge steam or the like, of a longitudinally movable valve for admitting steam or the like to said blower element, an intermeshing worm wheel and worm respectively connected to said blower element and valve for actuating the same, means for limiting 125

the rotation of said worm wheel in opposite directions, and a piston adapted to be subjected to the pressure of the steam, movable with said valve and arranged to effect an unbalanced force upon said valve when in open position acting in a direction opposite to that taken by the valve in moving to closed position, whereby rotation of said blower element is completed before said valve is moved from open position.

3. In a boiler cleaner, the combination with a rotatable blower element adapted to discharge steam or the like, of a valve for admitting steam or the like to said blower element, cooperating members for actuating said blower element and opening and closing said valve, means for limiting the movement in opposite directions of the member for actuating said blower element, and a piston in addition to said valve operating members operated by the steam or the like when said valve is in open position, said piston being connected to said valve to transmit an unbalanced force thereto acting in a direction opposite to that taken by the valve in moving to closed position, whereby the rotation of said blower element is completed before said valve is moved from open position.

4. In a boiler cleaner, a blower element, a valve controlling the flow of cleaning fluid to the said element, means for rotating the said element and for actuating the said valve, and a member in addition to said valve actuating means connected to the said valve adapted to be acted upon by the cleaning fluid supplied to the said element to influence the actuation of the said valve to cause the same to open before rotation of the element and to close after rotation of the element.

5. In a boiler cleaner, the combination with a blower element, a valve for controlling the flow of cleaning fluid to the blower element, and means for actuating said valve, of means separate from said valve actuating means for causing the cleaning fluid to influence the actuation of said valve by said valve actuating means.

6. In a boiler cleaner, a movable blower element, means for moving said blower element, a valve for controlling the flow of cleaning fluid to said blower element, means for moving the blower element and for actuating the said valve, and means constantly exerting a force on said valve tending to move the same independently of said valve actuating means to cause the valve to open before movement of the blower element and to close after movement of the blower element.

7. In a boiler cleaner, the combination with a blower element, and a fluid passage leading thereto, of a valve controlling the fluid passage and seating under pressure of the fluid in said passage, and means for em-

ploying pressure of the fluid to retard the initial seating movement of the valve.

8. In a boiler cleaner, the combination with a rotatable blower element adapted to discharge steam or the like, of a valve for admitting steam or the like to said blower element, cooperating members for actuating said blower element and opening and closing said valve, and resilient means for exerting an unbalanced force upon said valve in a direction opposite to that taken by said valve in moving to closed position whereby the valve is held from moving to closed position until the blower element has been returned to its original position.

9. In a boiler cleaner, the combination with a rotatable blower element adapted to discharge steam or the like, of a valve for admitting steam or the like to said blower element, cooperating members for actuating said blower element and opening and closing said valve, and a spring for exerting an unbalanced force upon said valve in a direction opposite to that taken by said valve in moving to closed position whereby the valve is held from moving to closed position until the blower element has been returned to its original position.

10. In a boiler cleaner, the combination with a rotatable blower element adapted to discharge steam or the like, of a valve for admitting steam or the like to said blower element, cooperating members for actuating said blower element and opening and closing said valve, and gravity actuated means for creating an unbalanced force acting upon said valve in a direction opposite to that taken by said valve in moving to closed position, said force being sufficient when the valve is in open position and the blower element is in adjusted position to compel the rotation of said blower element to its original position before the valve is moved from its open position.

In testimony whereof I affix my signature. 110
